(57) **CLAIM**

The ornamental design for a pet carrier with wheels, as shown and described.

DESCRIPTION

FIG. 1 is a front, left and top perspective view of a pet carrier with wheels, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the pet carrier with wheels in a usable state.

The evenly dashed broken lines illustrate environmental subject matter only and form no part of the claimed design. The dash-dot-dot-dash broken lines illustrate stitching and form part of the claimed design.
